UNITED STATES PATENT OFFICE.

EMANUEL E. ZIENNER, OF CHICAGO, ILLINOIS.

INDICATOR LAMP.

1,426,240.

Specification of Letters Patent. Patented Aug. 15, 1922.

Application filed March 9, 1922. Serial No. 542,386.

To all whom it may concern:

Be it known that I, EMANUEL E. ZIENNER, citizen of the United States, residing at Chicago, in the county of Cook and State of Illinois, have invented certain new and useful Improvements in Indicator Lamps, of which the following is a specification.

This invention relates to indicator lamps and more particularly to an improved 10 illuminated indicator lamp especially adapted for use at the front of homes and residences, to be mounted in a position where it will be readily observed from the street and be easily seen during the nighttime.

One of the objects of the invention is to 15 provide an indicator lamp of this character which will contain illuminated indications of the exact location and number of the residence to which the lamp is attached.

A further object of the invention is to 20 provide an indicator lamp of this character which may be readily adapted for illumination by gas, electricity, or an oil burner or lamp.

The invention further aims to provide a 25 structure for carrying the indicia which will firmly hold the same in position, whereby it will not vibrate or become broken during a hard wind or storm.

One of the objects of the invention is to 30 provide a device of this character by means of which residents, property owners, and voters, may cooperate with the officials of city statistic bureaus for assisting in maintaining accurate records of citizens and 35 voters, with respect to their removals or relocation thus enabling officials, in the thickly populated sections of cities and towns, to conduct elections, primaries, and 40 other meetings with dispatch and with less confusion in checking.

The invention also aims to provide a means whereby the steps or stairway leading up to the doorway of the residence may 45 be illuminated from the light rays furnished to the indicator.

Other objects will appear upon consideration of the following detailed description and the accompanying drawings herein:

Figure 1 is a perspective view of the apparatus constructed in accordance with my invention.

Figure 2 is a horizontal section.

Figure 3 is a vertical section taken approximately on the line 3—3 of Figure 2.

Figure 4 is a vertical section taken approximately on the line 4—4 of Figure 2.

Figure 5 is a perspective view showing the glass panel and the metallic plate in spaced relation.

Figure 6 is a detailed perspective view of the spring member for maintaining the glass and plates in rigid position.

Figure 7 is a detailed perspective view of the lamp bracket used for holding the oil-burning lamp in position when the same is used.

Figure 8 is a detailed view of a modified form of ventilator.

Figure 9 is a perspective fragmentary view illustrating the method of maintaining the hinged closures in closed position.

Figure 10 is a detailed view showing the relative angular positions of the brackets for mounting the device upon a wall.

Figure 11 is a detailed view of one of the single spring members.

Referring to the drawing by numerals, the body 1 consists of a casing 2 having a back or wall 3 upon which socket or cylindrical members 4 are mounted adapted to be received by spindles 5 which may be attached to the wall as indicated in Figure 10, so that the lamp may be mounted in position. The spindles 5 may be located in angular relation, whereby the water will readily drain from the lamp and also permit the illuminated faces to be slightly directed downwardly.

While it will be understood that the body 90 structure may be made to include any number of faces, the present illustration indicates the form utilizing two illuminated faces, which may be readily observed from either direction. Accordingly, the top 6 95 and the bottom 7 are substantially triangular in formation and the longitudinal edges of the top wall 6 are provided with copings 8 whereby the water may drain off the top without being permitted to enter the structure within the lamp body. The two closures 9 and 10 consist of substantially rectangular door frames 11 hingedly connected as indicated at 12 to the back wall 3, so that the doors may readily swing open. The forward marginal edges of the doors, as shown in Figures 3 and 9, are provided with sockets 13 and 14 having aligned openings when the doors are closed, the upper socket being equipped with a bayonet slot 15 through 110

tion or indicia on the sign or lamp may include any arrangement of the ward, precinct, number, street, or other desired inscription, may be varied and located in any 5 preferred manner.

What I claim is:

In an indicator lamp of the character described, a body structure having a back wall and open side walls and forming a 10 structure substantially triangular in cross section, hinged door frames mounted upon said side walls and adapted to meet at the

apex of said triangular body structure, each of the said door frames being equipped with sockets adapted to register with each other 15 for aligning the said sockets at the apex of the said body structure when the doors are closed, a locking pin in one of said sockets adapted to be received in the other socket to lock the doors at their meeting edges, 20 and a pair of sign plates attached to each door frame.

In testimony whereof I affix my signature.
EMANUEL E. ZIENNER.
